(57) **CLAIM**

The ornamental design for a lingerie, as shown and
described.

DESCRIPTION

FIG. 1 is a front, left side, top perspective view of a lingerie
showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front elevational view thereof when the lingerie
is opened; and,

FIG. 9 is a rear elevational view thereof when the lingerie is
opened.

The broken lines immediately adjacent to the claimed portions
are boundaries, all other broken lines are environmental
structures; all the broken lines form no part of the claimed
design.
